ABSTRACT

A dial for a timepiece, preferably a watch, the dial being provided with a relief portion which is made as an assembly of pieces on different levels, juxtaposed on a base, such that the relief portion is formed by the upper surfaces of the pieces. A method for manufacturing the dial with several separate pieces, the upper surfaces of the pieces being subjected to a polishing step and/or possibly an enameling step. The pieces are then cut along a defined contour and then assembled edge-to-edge on a base, so as to create the relief portion.

DIAL FOR TIMEPIECES

CROSS-REFERENCE TO RELATED APPLICATIONS

This application is a division of U.S. application Ser. No. 16/902,474 filed Jun. 16, 2020, which claims the benefit of priority from prior European Application No. 19189456.7 filed Jul. 31, 2019, the entire contents of each of which is incorporated herein by reference.

FIELD OF THE INVENTION

The present invention relates to a dial for a timepiece, particularly for a wristwatch, and more particularly to a polished and/or enameled dial of this type whose visible surface includes a relief portion.

STATE OF THE ART

It is well known to manufacture dials that have a relief portion, consisting, for example, of a conical or pyramidal part on the outside of a flat circular part. Dials of this type are generally made by machining in the base material of the dial, such as stone or ceramic, to obtain the three-dimensional shape, followed by polishing and/or enameling steps. One problem that is often encountered is that these polishing and enameling processes round off the edges between the relief surfaces after machining, which detracts from the aesthetic effect of the watch.

SUMMARY OF THE INVENTION

The present invention aims to provide a method for manufacturing a dial for timepieces which overcomes the problems identified above.

To this end, the invention proposes a method for manufacturing a dial for a timepiece, the dial comprising a relief portion, wherein the relief portion is produced as an assembly of pieces on different levels, juxtaposed on a base, such that the relief portion is formed by the upper surfaces of the pieces, the method including the steps consisting in:

- manufacturing semi-finished pieces by machining,
- treating said upper surfaces of the pieces after step a) to give the upper surfaces a defined aesthetic appearance.
- cutting said treated pieces along a contour of defined geometry.
- assembling the pieces obtained after step c), by juxtaposing the pieces on the base.

By applying surface treatment steps, in particular by polishing and/or enameling operations on machined and cut pieces prior to assembling said pieces on a base or substrate, the invention makes it possible to make the relief portions with straight edges at the junctions between the various pieces forming the dial.

The invention also concerns a dial for a timepiece, preferably for a watch, the dial being provided with a relief portion which is made as an assembly of pieces on different levels, juxtaposed on a base, such that the relief portion is formed by the upper surfaces of the pieces.

Other features and advantages of the present invention will appear in the following description of preferred embodiments, given by way of non-limiting example, with reference to the annexed drawings.

BRIEF DESCRIPTION OF THE DRAWINGS

FIG. 1 represents a watch dial comprising a relief portion, as currently known.

2

FIG. 2 represents the constituent pieces of a dial made according to the method of the invention.

FIGS. 3a-3c represent the dial assembly steps according to the method of the invention.

FIG. 4 represents another example of a dial made according to the method of the invention.

FIG. 5 represents an alternative embodiment for manufacturing the dial of FIG. 3c.

FIG. 6 represents a dial made according to the method of the invention comprising a base with different levels.

FIG. 7 represents a dial made according to the invention, comprising a negative relief portion.

FIG. 8 represents a dial made according to the invention comprising a local relief portion.

DETAILED DESCRIPTION OF EMBODIMENTS OF THE INVENTION

An illustration of a dial 1 as known in the state of the art is represented in FIG. 1. The dial comprises a one-piece part 9 comprising a flat lower surface 2, attached, for example by bonding, to a base or substrate 3 intended to be placed on top of a watch movement, for example by means of dial feet (not represented). The upper surface comprises a relief portion, including a flat central part 4 which is situated on a first level A1 measured from a horizontal reference plane which here is the plane of base 3, and twelve surfaces 5 inclined from first level A1 to a second level A2 outside dial 1, the second level A2 being lower than first level A1. The current known method for manufacturing this dial consists in machining a cylindrical part made of metal, stone, or ceramic, for example. After machining, inclined surfaces 5 and central surface 4 are polished. During the polishing operation, the edges between the surfaces of the relief portion become rounded and ill-defined, detracting from the aesthetics of the dial. Depending on the material of part 9, the method may also include a step of enameling the upper surface of the relief portion, this step applies notably when the dial is made of metal. Here too, the enameling operating will have the effect of rounding the edges.

To make the same dial by the method of the invention, several separate pieces are first manufactured by machining to produce basic semi-finished pieces having an upper surface. The upper surfaces of the elementary pieces are treated to give such elementary surfaces a defined aesthetic appearance. The upper surfaces of these elementary pieces are, for example, polished and/or possibly enameled. These upper surfaces can also be subjected to structuring treatments to form decorations such as Cotes de Geneve, stippling, circular graining, sand blasting, satin finishing, etc. Having undergone a treatment of their upper surface, the elementary pieces are then cut along a contour having a defined geometry, and then assembled on base 3 by juxtaposition, preferably edge-to-edge.

A set of elementary pieces made according to one implementation of the method of the invention is represented in FIG. 2: the set of these elementary pieces comprises a parallelepiped 10 having a thickness A1 and twelve straight side faces, in addition to twelve identical pieces 11 having a side face whose width corresponds to the width of the side faces of parallelepiped 10. The upper surface of pieces 11 is inclined between thickness A1 and A2. Thicknesses A1 and A1' can also be equal, but A1' is preferably slightly smaller or greater than A1, for example by several tens of a micrometre. Elementary pieces 10 and 11 can be manufactured using machining techniques known per se, such as grinding, laser ablation, ultrasonically assisted machining

and/or laser cutting. Upper surfaces **4** and **5** of pieces **10** and **11** then undergo a surface treatment to give the upper surfaces a defined aesthetic look, in this case polishing, using known state-of-the-art techniques, such as barrel, flat disc or fine wheel polishing.

When pieces **10** and **11** are made of metal or ceramic, the upper surfaces of the pieces can be wholly or partly, alternately subjected to an enameling step.

According to one embodiment, one-piece part **9** used in the state-of-the-art method illustrated in FIG. 1 is manufactured by machining according to a conventional method, polished, and then cut, for example by laser cutting, to obtain elementary pieces **10** and **11**.

The elementary pieces **10** and **11** obtained and whose upper surfaces **4** and **5** are polished and/or enameled are then assembled edge-to-edge, by placing them on base **3** of the watch, as illustrated in FIGS. 3a to 3c. Elementary pieces **10** and **11** are secured on the base by a method known per se, preferably by bonding or by a mechanical connection, such as by pins, or by a combination of such methods.

Preferably, parallelepiped **10** is mounted first, followed by side pieces **11** which are juxtaposed with the side faces of parallelepiped **10**, and with the faces of two adjacent pieces **11**. Polished and/or enameled pieces **10** and **11** are made with strict dimensional tolerances, such that gap-free contact is achieved for all the adjacent interfaces of the contiguous elementary pieces. Thus, this method makes it possible to make a dial **1** in relief with straight edges **12**, each of these edges **12** being defined by the junction between the apex lines **12a**, **12b** of two contiguous elementary pieces **10**, **11**.

FIG. 4 represents another example of a dial manufactured according to the method of the invention, and in which the relief portion is made by assembling two elementary pieces: a cylindrical piece **20** having a thickness **A1** and a conical piece **21** which forms a relief portion between **A1'** and **A2**, **A2** being smaller than **A1'** (the ratio between **A1** and **A1'** is the same as that described for the embodiment represented in FIGS. 2 and 3a-3c). The two pieces **20** and **21** are manufactured separately. Upper surfaces **4'** and **5'** are polished and/or enameled and then cut to final form. Pieces **20** and **21** are then assembled on base **3**.

FIG. 5 represents an example of the dial with twelve inclined surfaces, i.e. the same dial as represented in FIGS. 1 to 3 but made by assembling two pieces **10** and **31**: **45** parallelepiped **10** and a ring **31**. Ring **31** comprising twelve inclined surfaces **5** between **A1'** and **A2** is made as a one-piece part, preferably by laser cutting the part **9** represented in FIG. 1. Upper surfaces **4** and **5** of pieces **10** and **31** are then polished and/or enameled, then cut to final form **50** before being assembled on base **3**.

According to one embodiment, base **3** comprises several levels, and the thickness of the pieces which define the relief portion takes account of the height of these levels. FIG. 6 represents a dial assembled according to the method of the invention and which has the same external appearance of the dial of FIGS. 2 and 3a-3c, but wherein parallelepiped **10** is mounted on a central raised portion of base **3**. The level of the central portion of the base is higher than the level of external portion **33** of the base, on which pieces **11** are mounted.

It is also possible to make a negative relief portion by the method of the invention. An example is represented in FIG. 7. This dial includes four pieces **40** to **43** mounted on base **3**, which form a relief portion between a thickness **A1** outside the dial and a thickness **A2** smaller than **A1** at the centre of the dial.

The invention is not limited to the embodiments described above. The relief portion does not necessarily extend over the entire surface of the dial. An example of a local relief portion made by the method of the invention is illustrated in FIG. 8. The relief portion includes a central cylindrical piece **50** surrounded by a conical piece **51**, the pieces being integrated in a cylindrical hole **53** provided in flat dial **52**. The assembly of the relief portion is thus achieved by manufacturing pieces **50**, **51** and **52**, followed by polishing and/or enameling the pieces, cutting to form, and then assembling the pieces on base **3**.

The invention claimed is:

1. A method for manufacturing a dial for a timepiece, the dial comprising a relief portion, wherein the relief portion is made as an assembly of elementary pieces on different levels juxtaposed on a base, such that the relief portion is formed by upper surfaces of the elementary pieces, the method comprising:

a) manufacturing semi-finished elementary pieces by machining,

b) treating said upper surfaces of the elementary pieces after step a) to give the upper surfaces a defined aesthetic appearance,

c) cutting said treated elementary pieces along a contour of defined geometry,

d) assembling the elementary pieces obtained after step c), by juxtaposing the pieces on the base, wherein the relief portion extends over an entire surface of the dial,

wherein the relief portion is defined by a flat, polygonal, central surface which is situated at a first level measured from a horizontal reference plane, and a plurality of inclined side surfaces, which extend from a level essentially equal to the first level to a second level outside the dial, the second level being lower than the first level, a number of inclined surfaces corresponding to a number of sides of the polygonal surface, wherein one of said elementary pieces is a parallelepiped whose upper surface forms the polygonal central surface, and which has a number of side faces corresponding to the number of sides of the polygonal surface, wherein the parallelepiped is mounted centrally on said base, and

wherein each of the inclined surfaces is made by the assembly on said base of elementary pieces which are juxtaposed with the side faces of said parallelepiped.

2. The method according to claim 1, wherein step b) is a step of polishing, enamelling or structuring the upper surfaces of the elementary pieces to form a decoration.

3. The method according to claim 1, wherein in step d) the elementary pieces are juxtaposed edge-to-edge.

4. The method according to claim 1, wherein the relief portion is a local relief portion which is situated on one portion of the dial.

5. A method for manufacturing a dial for a timepiece, the dial comprising a relief portion, wherein the relief portion is made as an assembly of elementary pieces on different levels juxtaposed on a base, such that the relief portion is formed by upper surfaces of the elementary pieces, the method comprising:

a) manufacturing semi-finished elementary pieces by machining,

b) treating said upper surfaces of the elementary pieces after step a) to give the upper surfaces a defined aesthetic appearance,

c) cutting said treated elementary pieces along a contour of defined geometry,

5

d) assembling the elementary pieces obtained after step c),
 by juxtaposing the pieces on the base,
 wherein the relief portion extends over an entire surface
 of the dial,
 wherein the relief portion is defined by a flat, polygonal,
 central surface which is situated at a first level mea-
 sured from a horizontal reference plane, and a plurality
 of inclined side surfaces, which extend from a level
 essentially equal to the first level to a second level
 outside the dial, the second level being lower than the
 first level, a number of inclined surfaces corresponding
 to a number of sides of the polygonal surface,
 wherein the relief portion is formed by first and second
 elementary pieces of which:
 the first elementary piece is a parallelepiped whose 15
 upper surface forms the polygonal central surface,
 and which has a number of external side faces
 corresponding to the number of sides of the poly-
 gonal surface,
 the second elementary piece is a ring whose upper 20
 surface is formed by the plurality of inclined sur-
 faces, and which has a number of inner side faces
 corresponding to the number of sides of the poly-
 gonal surface,
 wherein the parallelepiped is mounted centrally on said 25
 base, and
 wherein the inclined surfaces are made by the assembly
 on said base of the second elementary piece juxtaposed
 with the first elementary piece.
 6. The method according to claim 5, wherein step b) is a
 step of polishing, enamelling or structuring the upper 30
 surfaces of the elementary pieces to form a decoration.
 7. The method according to claim 5, wherein in step d) the
 elementary pieces are juxtaposed edge-to-edge.
 8. The method according to claim 5, wherein the relief
 portion is a local relief portion which is situated on one 35
 portion of the dial.
 9. A method for manufacturing a dial for a timepiece, the
 dial comprising a relief portion, wherein the relief portion is
 made as an assembly of elementary pieces on different levels

6

juxtaposed on a base, such that the relief portion is formed
 by upper surfaces of the elementary pieces, the method
 comprising:
 a) manufacturing semi-finished elementary pieces by
 machining,
 b) treating said upper surfaces of the elementary pieces
 after step a) to give the upper surfaces a defined
 aesthetic appearance,
 c) cutting said treated elementary pieces along a contour
 of defined geometry,
 d) assembling the elementary pieces obtained after step c),
 by juxtaposing the pieces on the base,
 wherein the relief portion extends over an entire surface
 of the dial,
 wherein the relief portion is defined by a flat, circular,
 central surface which is situated at a first level mea-
 sured from a horizontal reference plane, and a conical
 surface, which extends from a level essentially equal to
 the first level to a second level outside the dial, the
 second level being lower than the first level,
 wherein the relief portion is formed by first and second
 elementary pieces of which:
 the first elementary piece is a cylinder whose upper
 surface forms the circular central surface,
 the second elementary piece is a ring whose upper
 surface is formed by said conical surface,
 wherein the cylinder is mounted centrally on said base,
 and
 wherein the conical surface is made by the assembly on
 said base of the second elementary piece juxtaposed
 with the first elementary piece.
 10. The method according to claim 9, wherein step b) is
 a step of polishing, enamelling or structuring the upper
 surfaces of the elementary pieces to form a decoration.
 11. The method according to claim 9, wherein in step d)
 the elementary pieces are juxtaposed edge-to-edge.
 12. The method according to claim 9, wherein the relief
 portion is a local relief portion which is situated on one
 portion of the dial.
